UNITED STATES PATENT OFFICE.

SAMUEL RITCHIE, OF LADYSMITH, WISCONSIN, ASSIGNOR OF ONE-THIRD TO
STANLEY L. CHICKER, OF LADYSMITH, WISCONSIN.

PORTABLE AUTOMATIC DOOR-LOCK AND BURGLAR-ALARM.

1,346,768.

Specification of Letters Patent. Patented July 13, 1920.

Application filed January 3, 1920. Serial No. 349,171.

To all whom it may concern:

Be it known that I, SAMUEL RITCHIE, a citizen of the United States, and resident of Ladysmith, in the county of Rusk and State 5 of Wisconsin, have invented certain new and useful Improvements in Portable Automatic Door-Locks and Burglar-Alarms; and I do hereby declare that the following is a full, clear, and exact description thereof.

10 My invention refers particularly to portable locks and it has for its object to provide a simple, economical and effective lock embodying means in connection therewith for giving an audible signal should an attempt be made to force the door or other 15 member which is locked, whereby the occupant of the room is warned that an attempt is being made to enter.

Other objects of my invention are to provide 20 a lock of this character which may be inserted against the floor and door member and there held firmly in place in such manner that pressure from the opposite side cannot displace it.

25 Another object is to provide an audible signal or burglar alarm associated with the lock mechanism so set and arranged that when an attempt is made to force the door, the alarm mechanism will automatically release and fire a blank cartridge.

Another object is to provide means in connection with the audible alarm for locking it or throwing it out of action when it is not desired for use.

35 Another advantage and object of this invention is to provide a simple lock of the friction grip character which can be readily removed and carried from place to place for use, such, for example, in hotels where the 40 ordinary standard locks are more or less out of order and furthermore this portable lock can readily be displaced thus avoiding the possibility of danger to the parties occupying a room from being locked in in case of 45 the standard lock becoming out of order or in case of emergency where it is desired to unlock the door quickly as, for instance, in fires or where quick exits are necessary.

50 My lock is furthermore of such dimensions that it can readily be carried from place to place.

With the above and other objects in view the invention consists in certain peculiarities of construction and combination of parts as 55 are hereinafter set forth with reference to

the accompanying drawings and subsequently claimed.

In the drawings—

Figure 1 represents a portion of a floor and door having a lock made in accordance 60 with my invention attached thereto and particularly showing the simple arrangement of connecting it.

Fig. 2 represents a somewhat enlarged 65 plan view of the door lock, and

Fig. 3 a detailed longitudinal sectional view through the various parts with certain parts broken away and other parts in full to more clearly illustrate the details of construction.

Referring by characters to the drawings, 70 1 represents a barrel having fixed therein at its lower end a three-pronged locking claw 2, the same being rigidly secured to the barrel. Mounted in the upper open end of the 75 barrel is a second locking claw 3 having a hollow shank 4 which is adapted to reciprocate within the barrel but is held against rotary movement by a screw-pin 5, which pin passes through the barrel and slots 5' 80 that are formed in the hollow shank thereof.

The barrel or body 1 is also formed with a cylindrical chamber 6 which extends from the upper portion of the body to a point 85 some distance from the lower portion of the barrel proper. The upper portion of this chamber 6 is provided with a cap 6' that is held in place by a pin 7, as shown, or other suitable means. Mounted in the chamber is a firing spring 8, the same being under compression between the cap 6' and a firing plunger 9, which plunger carries a hand-controlling button 10 that projects through a longitudinally disposed guide-slot 11 formed in one wall of the chamber. Adjacent to its lower end, the guide-slot is 90 formed with a right-angular extension 12 which constitutes a safety locking pocket for the shank of the button and the upper end of the slot is also provided with a similar locking pocket 13, which pocket is adapted to set the plunger in opposition to its spring pressure for firing. This operation is effected by simply pushing the plunger 95 upward and swinging the button to one side in such manner that its shank will seat within the pocket 13 of the slot and hold the plunger ready for firing. The plunger is tripped from its locked firing position by a cam finger 14, which cam-finger extends 100

110

downwardly from the upper or yielding locking claw 3 and obviously when the locking claw yields beyond a certain predetermined point the cam 14 will engage the shank of the plunger button and thus cause the same to be forced out of engagement with the pocket 13, whereby the spring will act to cause said plunger to shoot downwardly, being guided in its path by the longitudinal slot.

The lower end of the firing plunger carries a firing pin 15 which is adapted to pass through an aperture 15' in the closed lower end of the chamber 6. A magazine 16 is pivotally mounted to the shank portion of the fixed locking claw 2 by means of a screw or pin 17. The magazine is cylindrical in form and provided with a series of vent perforations 18 below its cartridge-receiving point and the lower end of said magazine is closed to prevent danger from the discharge therethrough of a wad from the cartridge or to prevent burning or sooting of the floor. The upper end of the magazine is formed with a reduced cartridge-receiving pocket 19.

When it is desired to load the magazine it can be swung downwardly to a position approximately at a right-angle with the body of the lock whereby access may be conveniently had to the loading pocket and the shell is then inserted therein. The magazine is then swung upwardly until it is in approximate alinement with the center of the firing chamber, as shown, and this position of alinement is insured by the upper portion of the magazine coming in contact with a semi-circular lip 20 which projects from the lower portion of the chamber 6. Thus it will be seen that when the parts are in this position the lock is ready for use.

As best shown in Fig. 1 of the drawings, to position the lock for use, the lower prongs thereof are set firmly into the floor at a predetermined distance from the door to be locked and the upper yielding claw is pressed into the door slightly, as shown, the spring permitting a normal slight tension so that the sharp prongs of the upper and lower claws are positively held against slippage and, in this position, the controlling button of the firing plunger is in juxtaposition to the cam. Should anyone at this time attempt to force the door from the opposite side, the upper prong will yield under abnormal pressure, tending to force the door inwardly and in so yielding, the cam will engage the plunger button, thus forcing it to rotate slightly, whereby it is forced from the upper locking pocket 13 and immediately the spring causes it to shoot downwardly and explode and the firing pin will thus discharge the cartridge so as to give an audible alarm and warn the occupant of

the room against burglars or others attempting to force the door open. Should it be desirable in some instances to temporarily dispense with the functioning of the audible alarm, it is only necessary for the operator to lock the plunger button in the lower pocket 12, such locking position being a sufficient distance from the tripping cam 14 to prevent the latter from releasing the plunger. Thus, although the audible alarm magazine is loaded, there will be no signal in case an attempt is made to force the lock.

Attention is also directed to the fact that the spring controlling the upper claw is of such resistance that when pressure is applied to the outside of the door, the spring will only yield slightly, if any at all, and will thus tend to embed the claws more firmly into their respective engagement with the floor and door to thus hold said door securely.

While I have shown and described the portable lock minutely with respect to all of its details, obviously these structural features may be varied within the knowledge of the skilled mechanic without departing from the spirit of my invention and it is understood that the lock may be of any desired size and material and also that the parts may be cast or stamped, which features depend upon the economical commercial problems that may hereafter develop.

I claim:

In an alarm lock comprising a hollow barrel closed at one end and having a claw extending therefrom, a grip claw having a shank in telescopic union with the open end of the barrel, means for holding the claw shank against rotary movement, a coil spring interposed between the claw shank and closed end of the hollow barrel structure, constituting a yieldable lock; the combination of a firing plug cylinder arranged parallel with the hollow barrel and secured thereto, the cylinder being provided with a longitudinal slot having a firing pocket at one end and a safety pocket at the other, a spring-controlled firing plug reciprocatively mounted in the cylinder, a button extending from the firing plug through the cylinder slot and adapted to be selectively fitted in the firing pocket thereof or the safety pocket, a cam finger carried by the telescopic claw shank and extending in a line of travel for engagement with the button, when the same is in the firing pocket of the cylinder slot, and a cartridge magazine mounted in the lower end of the firing plug cylinder.

In testimony that I claim the foregoing I have hereunto set my hand at Ladysmith, in the county of Rusk and State of Wisconsin.

SAMUEL RITCHIE.
